SAFETY DEVICE

Charles E. Blank, Painted Post, N. Y., assignor to
Ingersoll-Rand Company, Jersey City, N. J., a
corporation of New Jersey

Application October 5, 1938, Serial No. 233,408

5 Claims.

(Cl. 74—2)

This invention relates to engines and more particularly to a safety device associated with the pressure lubricating system of an engine.

This invention is an improved form of apparatus of the type disclosed in Patent No. 2,099,556 issued to A. O. Carpenter, November 16, 1937.

One object of the invention is to stop a steam engine automatically, and in an improved manner, when it is operating under conditions considered unsafe, more particularly when the pressure in the lubricating system drops to a value which would be too low to effectively lubricate the engine, either because of the low speed of operation of the engine or because of lack of lubricating oil.

Another object of the invention is to improve the form of such device by eliminating friction to a large extent to make the apparatus more compact, simpler, and cheap to construct.

Other objects of the invention will be in part obvious and in part pointed out hereinafter.

In the accompanying drawings and in which similar reference characters refer to similar parts,

Figure 1 is a side elevation, partly in section, of a preferred embodiment of the invention.

Figure 2 is a transverse section along the plane 2—2 of Figure 1, looking in the direction of the arrows,

Figure 3 is a cross section on the plane 3—3 of Figure 2, looking in the direction of the arrows, and

Figure 4 is a sectional view of part of the apparatus taken on the planes indicated by the line 4—4 of Figure 2.

Referring to the drawings, and particularly Figure 1, the safety device is particularly adapted to operate a steam valve, in this instance having a casing 10, housing a valve seat 12 upon which is adapted to seat a movable valve member 14 whereby communication between steam supply pipe 16 and a part 18 is adapted to be interrupted in an emergency. Valve member 14 is held off its seat by a pin 20 passing through an aperture 22 formed in an extension of valve 14, pin 20 being carried by an arm 24 pivotally mounted on a shaft 26 passing through the casing 24 and keyed to a weighted lever 28. As indicated in Figure 1, this valve is an emergency precaution and may be used in conjunction with the usual type of gate valve 30, details of which are not shown.

The weighted lever 28, as described above, is adapted in an emergency to close the valve 14 to its seat 12 quickly, and is normally held up to

keep the valve open by means of a latch 32 having a notch 34 to which a stud 36 is adapted to fit, the stud being bolted to the lever 28 as at 38.

Latch 32 is pivoted at a pin 40 mounted on a bracket 42 formed integrally with a trip release mechanism housing 44, which is attached by bolts 46 to the valve casing 10. Casing 44 is generally cylindrical in form and has an outer wall 48 upon which is mounted centrally thereof, a bearing pin 50 which serves to mount a cover 52, held in place on a reduced extension 54 of the pin 50 by means of a nut 56.

The trip release mechanism includes a pivotally mounted member or pendulum 58 having a weighted end 60, which causes the pendulum 58 to rotate when released. Suitable needles 78 between pin 50 and the pendulum member 58 provide a frictionless bearing for the latter. At the opposite end is a claw or hook-like projection 62 arranged to forcibly engage a pin 64 mounted at the end of a link 66 attached at its other end to latch 32 by a pin 68. The link 66 extends through an aperture 70 in the cover 52 and is guided on the wall 48 under a strip 72 (Figs. 2 and 4) held on to the wall 48 by bolts 74 and spaced therefrom by washers 76.

The link 66 is adapted to be retained in its disengaging position by a catch member 80 pivotally mounted on the upper bolt 74 and urged by a spring 82 attached at its other end to an ear 84 integrally formed with strip 72, to engage link 66. The notch 86 in the upper side of link 66 forms a detent to be engaged by catch member 80 when the hooked end 62 of the tripping member 58 draws link 66 inwardly of the cover 52.

Normally, the tripping member 58 is held in position so that its weighted end 60 is above the center of rotation or bearing 50 as shown in Figure 2. This is accomplished by a pin 88 slidably mounted in an aperture 90 in wall 48 and adapted to engage the trip member 58 at an aperture 92 in that member. The pin 88 is held in this engaging position by fluid pressure operated mechanism, in this instance comprising a drum having two heads 94 and 96, having a diaphragm 98 interposed between flanges 100 and 102 of heads 94 and 96 respectively, one of the chambers formed thereby, as for instance 104, being supplied with fluid under pressure from a source (not shown) by a pipe 106, said diaphragm 98 being arranged to exert pressure through a plunger 108 and a lever 110 against the end of pin 88. Diaphragm 98 is provided with a bearing plate 112 to contact plunger 108. A suitable bore 114 is provided in head 96 to permit reciprocatory

movement of plunger 108. Lever 110 is pivotally mounted as at 116 on a bracket 118 formed on the rear face of wall 48 and is attached to pin 88 by a pivot 120. The lever 110 is provided with an arm 122 attached to a spring 124, preferably of the coil type, tending to withdraw pin 88 and attached to an adjusting screw 126 passing through an aperture 128 in the casing 44, the tension of the spring 124 being regulated by a suitable knurled nut 130.

The drum consisting of heads 94 and 96 is held in position, facing wall 48, by suitable bolts 132 which pass through both of said heads and into a circular flange 134 formed integrally with the housing 44.

The trip member 58 is provided with a handle 136 by which that member is manually rotated for resetting. To provide clearance for handle 136, cover 52 is cut away at the periphery to form a slot 138. Trip member 58 is adapted to release catch 80 and to this end is provided with an abutment face 140 adapted to engage the ear 142 of catch 80 thereby rotating the catch to disengage the notch 86 of link 66. In this releasing position of trip 58 a painted spot 144 on the face of member 58 registers with a window 146 of cover 52.

For facilitating the initial setting of the trip member 58 a plunger 148 is provided in cover 52 slidably in a bore 150 to fit into an aperture 152 in the trip member 58. Aperture 152 is an enlarged sidewise extension of aperture 92 and is arranged to fit the enlarged head 154 of plunger 148. To limit the motion of plunger 148 and to accommodate head 154, a counterbore 156 is provided in a boss 158 of cover 52.

In order to insure proper positioning of the cover 52 with respect to the end wall 48, a notch 160 is provided in the wall to engage a tooth 162 in the cover.

To set the mechanism initially, the handle 136 is rotated counter-clockwise as far as it will go. This releases the catch 80 by pressure of the abutment 140 against the ear 142, thus extending spring 82. By its own weight the latch 32 drops outwardly against weighted lever 28, which is then raised manually until the pin 36 is engaged by the notch 34 of latch 32. It is impossible to raise the weighted lever 28 too high as this is prevented by the over-extending hook 164 of latch 32. By means of the handle 136 the trip member 58 is held in that position and, by the pressure of the operator's thumb, plunger 148 is pressed inwardly so that the head 154 of the plunger engages aperture 152 of the trip member. Handle 136 may then be released as the trip member 58 is thus held in position and this is indicated by observation of the colored spot 144 through the window 146.

60 Inasmuch as the valve 16 permits passage of steam to the engine (not shown), presumably the engine can be started by opening valve 30 and oil pressure for lubricating the engine will develop, as described more fully in the patent 65 above referred to. Fluid pressure provided by the lubricating oil and transmitted through pipe 106 to chamber 104 and acting against diaphragm 98 will press against plunger 108, which in turn will press against lever 110 to overcome the tension of spring 124. As sufficient lubricating oil pressure is developed, this pressure will cause lever 110 to push pin 88 into aperture 152 thereby disengaging plunger 148 and trip member 58 and permit slight rotation of that member due to 70 gravity, whereupon plunger 88 will engage aper-

ture 92 of the trip member to prevent further rotation, as indicated in Figure 2. In this position the colored spot 144 is no longer visible through window 146, which will indicate to the operator that the engine is functioning normally 5 and that the proper lubricating oil pressure is being developed.

Assuming now that the lubricating oil pressure drops so that the pressure against aperture 98 is insufficient to overcome the tension in spring 10 124, this permits plunger 108 to be retracted and, in addition, the plunger 88 will be withdrawn from aperture 92. Upon such release the weight of the pendulum-like trip member 58 causes that member to drop, bringing the hooked end 62 15 into engagement with pin 64 of link 66. The great force accompanying this engagement pulls latch 32 out of engagement with pin 36 which instantly causes lever 28 to drop and to close valve 14. This will, of course, shut down the 20 engine and the operator may restart it by following the procedure above described.

Thus by the above construction are accomplished, among others, the objects hereinbefore referred to.

Many modifications of the above described embodiment, which do not depart from the spirit of the invention, will occur to those skilled in the art. Such changes are intended to be included within the scope of the appended claims.

I claim:

1. In a latch mechanism adapted to be held inoperative by a pressure actuated device for a valve adapted to be closed by a gravity actuated lever comprising a latch to hold said lever in 35 unactuated position, a pivotally mounted member weighted at one end and held against gravity by said device, a catch on said pivotally mounted member, and a member carried by said latch and cooperating with said catch to actuate the latch. 40

2. In a latch mechanism adapted to be held inoperative by a pressure actuated device for a valve adapted to be closed by a gravity actuated lever comprising a latch to hold said lever in unactuated position, a support, a member pivotally mounted on said support and adapted to be held by said pressure actuated device with its 45 weighted end uppermost, a catch on said member, and a link attached to said latch and guided on said support adapted to be engaged by said catch for actuating the latch.

3. In a latch mechanism adapted to be held inoperative by a pressure actuated device for a valve adapted to be closed by a gravity actuated lever comprising a latch to hold said lever in 55 unactuated position, a support, a member pivotally mounted on said support and adapted to be held by said pressure actuated device with its weighted end uppermost, a catch on said member, a link attached to said latch and guided on 60 said support, and adapted to be actuated by said catch to release the latch, and means to engage said link to hold said latch in releasing position.

4. In a latch mechanism adapted to be held inoperative by a pressure actuated device for a valve adapted to be closed by a gravity actuated lever comprising a latch to hold said lever in unactuated position, a support, a member pivotally mounted on said support and adapted to be held by said pressure actuated device with its 65 weighted end uppermost, a catch on said member, a link attached to said latch and guided on 70 said support, and adapted to be actuated by said catch to release the latch, spring pressed means to hold said link in its latch releasing position, 75

said member being adapted to release said spring pressed means.

5. In a latch mechanism adapted to be held inoperative by a pressure actuated device for 5 a valve adapted to be closed by a gravity actuated lever comprising a support, a latch pivotally mounted on said support to hold said lever in unactuated position, a link guided by said support and adapted to withdraw said latch from 10 said lever, a spring pressed detent engageable with said link to hold said latch in releasing

position, a member pivotally mounted on said support and provided with a catch to engage said link, said member being arranged to disengage said detent, an aperture in said member engaged by the pressure actuated device to hold the weighted end of said member uppermost, and a manually operable plunger also engaging said member and adapted to be displaced by said pressure actuating plunger.
